Tujunga, Calif.

Application December 15, 1951, Serial No. 17,755

Term of patent 7 years

(Cl. D80—9)

To all whom it may concern:

Be it known that we, Preston K. Wood and Gwen A. Maurer, both citizens of the United States, residing at Arcadia and Tujunga, respectively, in the county of Los Angeles, State of California, have invented a new, original, and ornamental Design for a Display Rack, of which the following is a specification, reference being had to the accompanying drawing, forming part thereof, in which:

Fig. 1 is a perspective view of a display rack showing our new design;

Fig. 2 is a top plan view thereof;

Fig. 3 is a side elevation thereof as viewed from the left of Fig. 1; and

Fig. 4 is a rear elevation thereof.

We claim:

The ornamental design for a display rack, as shown.

PRESTON K. WOOD.
GWEN A. MAURER.
